UNITED STATES PATENT OFFICE.

EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

RIBBON MECHANISM FOR WRITING-MACHINES.

No. 859,294.

Specification of Letters Patent.

Patented July 9, 1907.

Application filed March 30, 1905. Serial No. 252,819.

To all whom it may concern:

Be it known that I, EDWARD B. HESS, a citizen of the United States of America, residing in the borough of Brooklyn, city and State of New York, have invented certain new and useful Improvements in Ribbon Mechanism for Writing-Machines, of which the following is a specification.

This invention comprises a new organization where-
in either the right or left ribbon bobbin may, at will,
10 be driven from the geared cover of the spring box, or
both be disengaged therefrom to permit manual wind-
ing of the ribbon,—all as appears from the following
description, and from the accompanying drawings, in
which,

15 Figure 1 is a top plan view: Fig. 2, a bottom plan
view: Fig. 3, a transverse vertical section on line 3, 3,
of Fig. 1: Fig. 4, a longitudinal vertical section on line
4, 4, of Fig. 3: Fig. 5, a detail section of the ratchet
device to prevent back winding of the ribbon when
20 the carriage is returned for commencement of a new
line of printing: and Fig. 6, a section on line 6, 6, of
Fig. 5.

The spring box μ is properly mounted and provided,
as usual, with a wheel and worm adjusting means b .
25 Its circular cover is provided with peripheral gear
teeth c with which meshes a pinion d on a horizontally
arranged shaft d' . The end of this shaft has a bearing
at d' in one arm of the bracket that supports the spring
box and has sufficient play to permit slight oscillation
30 of the shaft. The shaft extends toward the front of the
machine and is provided at its forward end with a
worm e adapted to mesh, when in its depressed position,
with a vertically disposed gear f on the end of a
transverse shaft f' which, through the pair of gears g ,
35 drives the vertically disposed spindle g' of the right
hand ribbon bobbin. When the shaft d' is, however,
thrown to its uppermost position, the worm thereon
engages a horizontally disposed gear h connected with
the vertical spindle g^2 of the left hand ribbon bobbin.

40 To provide for these two adjustments of the shaft d'
and for an intermediate position thereof in which its
worm is out of gear with either gear, the front end of the
shaft is mounted in the laterally extending arm i of a bell crank lever
45 upwardly extending arm i^2 may be actuated in the fol-
lowing manner. On the side of the upper end of the
arm is pivotally secured an apertured block j . A
downwardly extending pin k passes loosely through
the aperture in the block and is secured at the upper
50 end to a rocking arm m pivotally mounted in the
bracket n of the left hand ribbon box and having a
handle m' . By throwing the handle to the right as
viewed in Fig. 3, the lower lateral arm i of the rock-
ing shaft is thrown upwardly so that the worm e engages
55 the gear h on the spindle of the left hand ribbon bobbin.

By throwing the handle to the left, the upright arm
of the bell crank may be thrown over to the right and
the lateral arm i downwardly to bring the worm e into
engagement with the gear f on the transverse shaft f' .

A spring k' surrounding the pin k and bearing upon
the block j serves to firmly hold the parts in their de-
scribed positions. The axis i' of the bell crank is
vertically below the axis of the rocking arm m and,
when the upright arm of the bell crank is brought into
parallelism with a line connecting these two axes in 65
which position it will be held by the spring k' , the
arm i of the bell crank will be held in an intermediate
position in which the worm e will be out of engagement
with both gears h , f , when the ribbon may be manually
manipulated.

Ribbon guide brackets o , o , secured to the supports
provided for the ribbon spool, have their ends disposed
at an angle of about forty-five degrees. Such angular
edges are turned up vertically and formed with ribbon
guide slots v' , as indicated in Fig. 1. These 75
forked guides serve to direct the ribbon to the printing
point at an angle of about forty-five degrees and pre-
vent slackness of the ribbon when the feed is rapidly
operated. They also serve to keep the ribbon from
dropping from the spool. To prevent backward move- 80
ment of the ribbon when the carriage is returned to
the initial position for printing of a new line, the gear
 d is connected with the shaft d' by means of a ratchet q ,
(Fig. 6) inclosed in a cup q' arranged between the
ratchet wheel d and the end bearing of the shaft. 85

I claim as my invention:

1. In a ribbon mechanism for a writing machine, the
combination of the spring drum having a rotatable plate
formed with gear teeth, an oscillatable shaft having at
one end a pinion gearing with the plate, a worm on the 90
opposite end of the shaft, a gear adapted to drive one of
the ribbon bobbin spindles, a gear connected by a driving
connection with the other ribbon bobbin spindle and
means for oscillating the shaft to bring it at will into
connection with either of said gears. 95

2. In a ribbon mechanism for a writing machine, the
combination of the spring drum having a rotatable plate
formed with gear teeth, an oscillatable shaft having at
one end a pinion gearing with the plate, a worm on the
opposite end of the shaft, a gear adapted to drive one of 100
the ribbon bobbin spindles, a gear connected by a driving
connection with the other ribbon bobbin spindle and
means for oscillating the shaft to at will bring it into
connection with either of said gears and to hold it at will
in intermediate position out of engagement with either 105
gear.

3. In a ribbon mechanism for a writing machine, the
combination with the rotatable part of the spring box having
peripheral gear teeth, of a pinion meshing therewith,
a shaft driven by the pinion, a worm on the shaft, a ver- 110
tically rocking arm in which the end of the shaft is
mounted, a vertically disposed gear, a driving connection
between it and one of the ribbon bobbin spindles, hori-
zontally disposed gear adapted to drive the other ribbon
bobbin spindle and means for moving the vertically rock-
ing arm to throw the worm into engagement with either 115

the horizontally or vertically disposed gears to drive at will the spindle of either ribbon bobbin.

4. In a ribbon mechanism for a writing machine, the combination with the rotatable part of the spring box having peripheral gear teeth, of a pinion meshing therewith, a shaft driven by the pinion, a worm on the shaft, a vertically rocking arm in which the end of the shaft is mounted, a vertically disposed gear, a driving connection between it and one of the ribbon bobbins, a horizontally disposed gear adapted to drive the other ribbon bobbin spindle, means for moving the vertically rocking arm to throw the worm into engagement with either the horizontally or vertically disposed gears to drive at will the spindle of either ribbon bobbin and means for holding said arm in intermediate position with the worm out of engagement with either of said gears.

5. In a ribbon mechanism for a writing machine, the spring box having a rotatable part with peripheral gear teeth, a pinion gearing therewith, an oscillatable shaft driven by the pinion, a bell crank lever in one arm of which the end of the shaft has a bearing, means for rocking the other arm of the bell crank lever to oscillate the shaft and gears adapted to respectively drive the spindles of the ribbon bobbins and with either of which the worm may at will be thrown into engagement.

6. In a ribbon mechanism for a writing machine, the combination of the spring box having a rotatable part with peripheral gear teeth, a pinion gearing therewith, a shaft driven by the pinion, a worm on the shaft, two gears adapted respectively to drive the ribbon bobbin spindles and means for at will throwing the worm into engagement with either gear.

7. In a ribbon mechanism for a writing machine, the combination of the spring box having a rotatable part with peripheral gear teeth, a pinion gearing therewith, an oscillatable shaft driven by the pinion, a bell crank lever in the laterally disposed arm of which said shaft has a

bearing, a rocking pin slidably connected with the upright arm of the bell crank and adapted to rock it in either direction, a spring acting to hold the upright arm of the bell crank in the positions in which it may be set and means whereby the spindle of one ribbon bobbin may be driven when the oscillatable shaft is in one position and the other ribbon bobbin spindle be driven when the oscillatable shaft is in another position.

8. In a ribbon mechanism for a writing machine, the combination of the spring box, an oscillatable shaft having one end, operatively connected therewith and driven thereby, a worm on the shaft, ribbon-bobbin driving gears, one for each bobbin, with either of which said worm may be moved into engagement, and a ratchet and pawl device to prevent back motion of the shaft when the carriage of the machine is returned to initial position for the printing of a new line.

9. In a writing machine, a ribbon mechanism comprising a pair of ribbon bobbins adapted to be independently driven, their respective driving gears arranged in juxtaposition at an angle to each other, and a laterally movable driven worm adapted to, at will, be thrown into engagement with either of said driving gears.

10. In a writing machine, a ribbon mechanism comprising a pair of ribbon bobbins located respectively at opposite sides of the machine, a pair of bobbin driving gears both located at one side of the machine in juxtaposition to each other and operatively connected with their respective bobbins, and a driven adjustable gear adapted, at will, to be set in engagement with either of said bobbin driving gears.

In testimony whereof, I have hereunto subscribed my name.

EDWARD B. HEISS.
